UNITED STATES PATENT OFFICE.

CHARLES KUDERER, OF PITTSBURGH, PENNSYLVANIA.

MOTORCYCLE-BACKREST.

1,348,121.

Specification of Letters Patent. Patented July 27, 1920.

Application filed December 9, 1918. Serial No. 265,893.

To all whom it may concern:

Be it known that I, CHARLES KUDERER, a citizen of the United States, residing at Pittsburgh, in the county of Allegheny and State of Pennsylvania, have invented new and useful Improvements in Motorcycle-Backrests, of which the following is a specification.

This invention relates to a motorcycle backrest whereby the back of a rider will be supported and has for its primary object to provide an improvement over that form of my invention illustrated in my copending application, filed August 5th, 1918, Serial Number 248,440.

An object of the invention is to provide means for automatically moving the supporting element to operative or inoperative position and to give resiliency to the supporters.

Besides the above my invention is distinguished in the manner of supporting and associating the elements so that the supporters may have a plurality of movements in all directions for obvious reasons.

With these and other objects in view the invention will be better understood from the following detailed description taken in connection with the accompanying drawing wherein:

Figure 1 is a vertical sectional view through one of the supporting devices, the other not shown as it is of identical construction with the one illustrated.

Fig. 2 is a diagrammatic view illustrating three positions that the supporter may assume.

Fig. 3 is an elevation of the device.

Figs. 4 and 5 are views of an arm for holding the supporter in an inoperative position, that is to say the dotted horizontal position shown in Fig. 2.

Again referring to the drawing the numeral 1 designates a vehicle seat of a motorcycle. To the seat 1 is connected a rod 2 which may be of a construction illustrated in the above mentioned application. This rod 2 has fixed thereto a cam plate 3 having a cam surface 3^a. Rotatably mounted on the rod 2 adjacent the plate 3 is a bracket 4 having a slot 5 slidably receiving a supporter 6. Hinged to a projection 7 of the bracket 4 is a link 8 also having a yieldable connection with the bracket by means of springs 9. Thus it will be seen that the link 8 is drawn toward the bracket 4 and

any downward swinging movement of the link 8 will be resiliently opposed. The link 8 is provided with a pin 10 adjustably associated with notches 11 in the supporter 6. Thus it will be seen that the supporter 6 is adjustably and resiliently associated with the bracket by means of the link 8 and springs 9.

Leaf springs 12 and 13 are provided connected to the link 8 and continuously bearing against the supporter 6 in a manner that the former will detachably hold a notch 11 associated with the pin while the latter will move the supporter 6 toward the body of the rider.

Slidably supported by the bracket 4 between the cam plate and supporter 6 is a pin 14 one end of which, is arranged to be engaged and moved by the cam surface 4 while the other end bears against the supporter 6 for moving the same laterally against the action of the spring 13 until the supporter assumes practically a position at right angles to the adjacent surface of the bracket 4 so that the supporter 6 will lie substantially parallel to the rear wheel of the motorcycle when thrown to an inoperative horizontal position as illustrated in Fig. 2.

When in this position the supporter 6 is received by a hook 16 carried by an arm 15 extending rearwardly from plate 3 and is held in the hook by a spring 16. From the foregoing description taken in connection with the accompanying drawing it should be apparent that I provide a device that may be thrown to a number of inoperative positions as illustrated in Fig. 2 and which will have the proper resiliency when associated with the arm pits of a rider and besides the supporters will be given the necessary lateral movements so as to be properly positioned with relation to the rear wheel of a motorcycle.

It is of course to be understood that the parts may be constructed and associated in other manners than shown such as changing the construction for accomplishing a cam action between the supporter 6 and rod 2 and the yieldable manner of connecting the supporter 6 to bracket 4 therefore, I do not desire to be limited in any manner except as set forth in the claims hereunto appended.

Having described my invention, what I claim is:

1. In a device of the character described,

- a fixed member, a bracket movable about the same, a supporting member rockably connected to the bracket, and coöperating means carried by said fixed member and the bracket
- 5 for moving said supporting member into a predetermined position about its axis of rocking movement and holding it in this position when the bracket is turned into a predetermined position about the fixed member.
- 10 2. In a device of the character described, a fixed rod, a cam member secured to said rod, a bracket loosely mounted on said rod, a supporting member pivotally connected to the bracket for movement toward and
- 15 away from the rod, and a member carried by the bracket and mounted to be moved by the cam member in a predetermined direction and to move the supporting member into a predetermined position and hold it in
- 20 this position when the bracket is turned into a predetermined position about the rod.
3. In a device of the character described, a fixed rod, a plate secured on the rod and provided with a cam element, a bracket
- 25 loosely mounted on the rod adjacent the cam face of said plate, a supporting member rockably mounted in the bracket for movement toward and away from the rod, and a pin slidable in the bracket with one end
- 30 in contact with the plate and its other end adjacent the supporting member whereby by turning the bracket about the rod the pin will be forced inwardly of the bracket by
- 35 said cam element so as to move the supporting member into predetermined position in the bracket and hold it in this position.
4. In a device of the character described, a fixed rod, a plate secured on said rod and provided on its outer face with a cam element, a bracket loosely mounted on the rod adjacent the outer face of the plate, a supporting member pivotally connected to said bracket for rocking movement toward and away from the rod, and a pin slidable
- 45 through the bracket of such length and so positioned as to contact with the supporting member above the pivot thereof so as to rock said member outwardly in the bracket and hold it in this position when said bracket
- 50 is turned about the rod so as to cause the inner end of the pin to contact with said cam element.
5. In a device of the character described, a fixed rod, a plate secured on said rod, a bracket loose on the rod adjacent said plate, a supporting member rockably mounted in the bracket, an arm extending horizontally from the plate and provided with a member for receiving and supporting the outer end
- 55 portion of said supporting member when rocked into substantial horizontal position, and coöperating means carried by said plate and the bracket for moving the supporting
- member into position to engage into the receiving and supporting means of said arm
- 65 when the bracket is turned about the rod so as to move the supporting member into parallelism with and adjacent the arm.
6. In a device of the character described, a fixed rod, a plate secured thereon and having a cam element on its outer face, a bracket loose on the rod, a supporting member extending through the bracket and connected thereto for movement toward and away from the rod, and a pin slidable in the bracket
- 70 with one end in contact with the cam face of the plate, said pin being of such length and so positioned as to contact with the supporting member so as to force the same outwardly when the pin is forced inwardly of
- 75 the bracket by contact with said cam element, the cam element being positioned for contact with the pin when the bracket is turned into substantial horizontal position.
7. In a device of the character described,
- 80 a fixed rod, a plate secured thereon and provided on its outer face with a cam element, a bracket loosely mounted on the rod adjacent the outer face of the plate, a pin supported transversely of the bracket at the
- 85 lower end thereof, a supporting member extending through the bracket and provided with a plurality of downwardly and outwardly inclined notches in its outer edge adapted to receive the pin for adjustably and rockably connecting the supporting member to the bracket, the top of the bracket being slotted to accommodate said supporting member, and a locking pin slid-
90 able through the inner wall of the bracket and having one end in contact with said plate and its other end in contact with the supporting member, said locking pin being positioned above the pin for the supporting member and the cam being positioned to force the locking pin into the bracket when
- 95 said bracket is turned into horizontal position so as to rock the supporting member into its outer position in the bracket and hold it in this position.
- 100 8. In a device of the character described, a fixed rod, a cam plate fixed thereto, a bracket rotatably mounted on the rod adjacent the cam plate, a link pivoted to the bracket, a supporter slidably mounted in the bracket and adjustably connected to the link, elements yieldably connecting the link to the bracket and a pin slidably mounted in the bracket and arranged to engage the cam plate and the supporter for moving the latter in a predetermined direction upon movement of the bracket in a predetermined direction.
- 105 In testimony whereof I affix my signature.
- 110
- 115
- 120

CHARLES KUDERER.
